CLAIM

The ornamental design for a side view camera for vehicle, as shown and described.

DESCRIPTION

FIG. 1 is a perspective view of a side view camera for vehicle showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a view illustrating a state in which the camera portion of the side view camera for vehicle is rotated 90 degrees counterclockwise.

The broken lines in the drawings depict portions of the side view camera for vehicle and form no part of the claimed design.

1 Claim, 8 Drawing Sheets
